2,442,471

SYSTEM FOR HANDLING MASSECUISTE

Eugene Roberts, Hastings, N. Y., assignor to The
Western States Machine Company, Hamilton,
Ohio, a corporation of Utah

Application March 27, 1943, Serial No. 480,790

4 Claims. (Cl. 127—19)

1

This invention relates to installations for the treatment of sugar massecuite in sugar factories at the stage of crystallization and crystal recovery, and particularly to improvements in methods and apparatus for handling pan boilings or strikes of massecuite between the vacuum pans where the massecuite is formed and centrifugal machines where the crystal recovery is carried out.

White massecuites and similar "free-purging" sugar mixtures are centrifuged as soon as practicable after being prepared, but a batch of 1000 to 3000 cubic feet usually is formed by each pan boiling, and it takes an hour or two to centrifuge such a strike. The boiled strike usually is passed from the vacuum pan through a trough into an open-top tank, called the "mixer," which holds the massecuite awaiting treatment and from which charges are drawn off, as needed, through loading gates on spouts at the tank bottom for treatment in underlying centrifugal machines. Meanwhile, another strike is boiled in the same vacuum pan.

It is desirable that every charge from each strike be centrifuged in the same way, and that uniform sugar and syrup products of the best attainable qualities be produced from all of the many charges. The practices used heretofore, however, fall short of this objective. In many installations some of the charges delivered from the mixer are more difficult to purge, wash and dry in the centrifugals than others, and these reduce operating efficiency and make the sugar and syrup products non-uniform. Also, the massecuite sometimes is difficult to load into a slowly rotating centrifugal basket and tends to form a sugar wall too thick at the basket bottom, which delays operations and results in off-grade products. Troubles of these kinds are particularly noticeable in the treatment of higher purity or white massecuites, which, with the use of comparatively recent massecuite conditioning and centrifuging processes, are boiled at higher temperatures and to higher density than was the practice a few years ago.

The object of my present invention is to provide new and useful improvements in the methods and equipment used to handle strikes or runs of sugar massecuite which will overcome or greatly reduce those difficulties and non-uniformities still encountered with existing sugar house practices and thus enable the sugar of each strike to be recovered with optimum efficiency by the operation of centrifugal machines.

I have found that the troubles above-mentioned

2

are largely attributable to the presence of false grain or smear in charges of massecuite as delivered from the mixer into the centrifugal machines, and that this false grain is the result, not of poor boiling operations in the vacuum pan but of chilling influences which affect portions of the massecuite between the time of dropping the strike from the pan and the completion of the centrifugal operations. High purity white massecuite, for example, can be boiled carefully to a density of 90 to 90 Brix with fine crystals of relatively uniform size substantially free from false grain, but as the massecuite passes from the pan into the mixer some of it is chilled by the ambient air, and when the mass enters the mixer a considerable amount of it is chilled by contact with the internal mixer parts. Further, as the centrifuging progresses, the massecuite undergoes rapid local heat losses to the air—through the mixer walls, from the surface of the mass and from continually exposed parts of the stirring mechanisms now generally used in the upper portion of the mixer to cooperate with heating and stirring means in the bottom and keep the mixer contents in circulation. These chilling effects are especially noticeable under cold weather conditions. Though the general temperature changes they cause may be small, or may be nullified by the action of massecuite heating means, they nevertheless cause smear formation and debase the purging qualities of any centrifugal charges containing the smear or false grain. When false grain has thus formed it is not affected by the action of massecuite stirring and heating means, but remains as an uncontrollable contaminant that is removed, if at all, only at the expense of excessive waste and costs in the centrifugal operations.

According to the present invention, I provide a new method and new apparatus for carrying out the same that eliminate the formation of false grain and other obstructions to efficient sugar recovery by overcoming the chilling influences and other irregularities which heretofore have affected each strike after the boiling of the strike in the vacuum pan, and which I have found to be the main cause of false grain formation and the resulting troubles described above.

I prevent cooling shocks and attendant false grain formation in the massecuite after it leaves the vacuum pan by heating the interior of the mixer when it is empty to a temperature at least approximately as high as the final boiling temperature applied to the strike in the pan and by

conveying each boiled strike directly from the pan into such heated mixer; and I prevent localized chilling in the massecuite held in the mixer awaiting centrifugal treatment, and keep the entire contents of the mixer uniformly subject to such slow heat exchanges as may be allowed or caused to take place during the centrifuging, by covering the mixer structure so as to keep its contents completely enclosed against the access of outside air and insulating the structure, over substantially all its external or heat-radiant surfaces, against chilling heat losses from the mixer contents to the ambient air. In addition, I preferably drop each strike directly from the pan into the preheated mixer tank through a downcomer which joins or seals together the two units and excludes the outside air from any chilling contact with the flowing massecuite. Thus, the mixer is made as an attachment or auxiliary to the vacuum pan, and the temperature and heat exchange conditions throughout the mass in the mixer are established and maintained in a definite predetermined relationship to the condition of the same mass as it was prepared in the pan.

The heating of the mixer interior to condition it for receiving a strike may be carried out in various ways. A suitable procedure is to steam the mixer interior. In a suitable embodiment of apparatus for that purpose I provide one or more steam pipes which open to the inside of the mixer structure, and where the mixer tank is equipped with conventional types of loading spouts a steam pipe preferably is extended through each loading spout wall. In such an embodiment steam is introduced into the mixer for a few minutes after the completion of the centrifuging of one strike and just before the dropping of the next strike into the mixer, and the steaming is continued until the mixer interior has been heated at least to about the final boiling temperature used in the vacuum pan.

When the preheated condition of the mixer is thus established by steaming, several important results and advantages may be obtained. The most important is the elimination of cooling shocks and false grain formation in the massecuite received for centrifugal treatment. Another is that the steaming removes such sugary material as may adhere to internal walls or parts of the mixer after the centrifuging of a strike, by rendering the adhering material fluid through the combined action of heat and condensation. The resulting fluid material may be drawn off through the loading gates in the course of the steaming, at a very substantial saving of grain melt or dilution heretofore caused by the washing down of mixer parts with water between strikes. A third function is that the steaming exerts a sterilizing effect on all of the internal mixed parts and thus relieves the problem of bacterial contamination.

To alter an existing factory installation pursuant hereto, the usual mixer tank is fitted with a cover completely enclosing its interior with the exception of an opening through which to admit massecuite into the tank, and this opening is surrounded by a downcomer directly connecting and sealing the mixer structure with the bottom of an overlying vacuum pan. The heat-radiant surfaces of the mixer structure are suitably insulated against substantial losses of heat therethrough from the massecuite, such as by overlaying the mixer side, end and bottom walls and also the cover with layers of heat-insulating

sheet material, or by forming the walls as jackets to hold a suitable insulating or heated fluid. When a steaming operation is to be used for pre-heating, one or more steam pipes are extended through the mixer walls, preferably with a pipe at the lower side of each loading spout. In addition, the mixer is provided with suitable stirring and heating means to maintain the massecuite awaiting centrifugal treatment in continuous circulation and regulate the temperature of the successive charges delivered to the adjacent centrifugal machines. These means, for example, may be of the types disclosed in United States Patents Nos. Re. 20,556, 2,086,951, 2,128,873 and 2,206,237.

I also have found it advantageous to construct the mixer itself so as to prevent any substantial dormant portions or pockets of massecuite from existing in the mixer. When using conventional structures some of the massecuite lies relatively dormant in parts of the mixer, such as in the spouts extending between the tank proper and the loading gates, and also in the lower corners of the tank in many cases. Under these conditions the sugar crystals in a hot massecuite of high purity tend to segregate or settle from the syrup, and the resulting non-uniform crystal and syrup distribution causes trouble in the loading of the centrifugal machines. I may overcome this trouble, for example, by making the loading spouts exceedingly short with their loading gates disposed closely adjacent to the bottom of the tank proper, so that a continuous forced circulation of heated massecuite is maintained by heating and stirring means in the tank bottom, substantially up to the inside faces of the loading gates. If needed, I also provide fillets in the corners of the tank to present curved or streamlined inside surfaces for efficient massecuite circulation. All massecuite in the mixer thus may be kept in effective forced circulation and subject uniformly to any physical changes that may occur or be caused to take place. To secure the same effect in conventional mixer installations having long goosenecks or loading spouts, modified forms of construction may be used, such as disclosed in my co-pending application, Serial No. 480,789, filed of even date herewith now Patent No. 2,411,138.

The foregoing and other objects, features and advantages of my invention will become more apparent from the following description of an illustrative embodiment thereof when considered in connection with the accompanying drawings, wherein

Figure 1 is a front elevation, partly in section, showing diagrammatically one form of a sugar recovery installation embodying my invention;

Figure 2 is an end elevation, partly in section, taken substantially along line 2-2 of Figure 1; and

Figure 3 is an enlarged fragmentary cross-section through an upper corner of the mixer tank showing illustrative details of construction.

In the drawings I have illustrated a sugar recovery station of a type designed for the handling and treatment of white or other free-purging massecuite that is to be dropped directly from a vacuum pan A into a mixer B and to be held by the mixer in a desired physical condition during the processing of the massecuite charge by a charge in underlying sugar centrifugals C. The mixer structure includes an elongated tank body 2 which is usually U-shaped in cross-section, together with a plurality of loading gates 4

of any desired construction which are connected with the bottom of the tank through very short spouts 6 so that the inside faces of the loading gates are closely adjacent to the zone of action of rotary heating and stirring means 10 disposed lengthwise in the bottom of the tank. The means 10, as shown, comprise spiral coils 12 mounted on a rotary shaft 14, together with provisions (not shown) for circulating hot water or other suitable heating fluid at a regulated temperature through the rotating coils, as disclosed, for example, in the aforesaid Patent Re. 20,556.

Above these heating and stirring coils are rotary stirring means 16 which also extend substantially the full length of the tank in its upper portion and coat with the means 10 to keep the main body of massecuite held in the tank in continuous circulation. The stirring means 16 comprise paddles or blades 17 mounted on radial arms 18 for rotation with a shaft 19, which may be driven from a source (not shown) common to the heating and stirring means 10. The depicted arrangement of heating and stirring devices is similar to that disclosed in my aforesaid Patent 2,127,873.

The mixer tank 2, as shown, is fitted with a cover 20 which extends across the entire top of the tank and may be provided, if desired, with hinged doors, such as shown at 21 and 22, permitting access to the interior of the tank. An opening 24 in this cover affords passage for the entrance of massecuite into the mixer when a strike is dropped, in the usual manner, from the vacuum pan A at the completion of a pan boiling. Opening 24, however, is surrounded by a downcomer 26, shown diagrammatically in Figures 1 and 2 and of any desired construction, which connects and seals the mixer structure directly with the bottom of the vacuum pan so that a strike being dropped from the pan passes as quickly as practicable into the mixer and is excluded altogether from contact by the ambient air.

The heat-radiant end, side and bottom walls of the tank 2 and the cover 20 are all formed with one or more layers of heat-insulating material, or with other suitable heat-insulating means, to prevent objectionable losses of heat from the mixer interior both before and during the processing of a strike. An illustrative manner of insulation is depicted in Figure 3. The wall of tank 2, for example, is overlaid by asbestos-magnesia blocks 30, which may be fastened to the wall by means of anchors 31 and wire netting 32 overlying the blocks. The netting in turn may be coated with one or more layers of insulating plaster, such as indicated at 33. The cover also might be so constructed, but is shown as comprising one or more layers 35 of wooden board coated on the outside with an asphaltic paint or the like, at 36, and overlaid on the underside by one or more layers of a suitable insulating board, such as asbestos board 37. With this or other equivalent heat insulation and with the cover 20 completely enclosing the mixer against the access of outside air, a structure is obtained which undergoes heat losses only at an exceedingly slow rate, so that the interior of the mixer can be kept heated in readiness to receive a strike of massecuite from the pan A, such as by the means described below, and so that cooling of massecuite in the mixer cannot take place at a rate sufficient to chill local por-

tions of the massecuite and cause objectionable false grain to form.

At the lower portion of the mixer one or more steam pipes are provided which extend through the mixer wall so as to introduce steam to the interior when desired. As shown, pipes 40 open into the bottom of the mixer at the opposite end walls and the center of the tank, and similar pipes 40a open into the bottoms of the spouts 6 (Figure 2). By these or equivalent means a large volume of steam may be admitted into the mixer at the end of the centrifuging of a strike, with the results of pre-heating the interior in readiness to receive the next strike and of removing any sugar crusts remaining on the mixer walls or the stirrer parts from the previous strike, as described hereinabove. In the course of the steaming the loading gates 4 may be held partly open so that the fluid material, produced from such crusts by the steaming will drain out of the spouts 6 for such further disposal as may be desired to recover its sugar content.

With the improvements herein set forth I am able to achieve several important advantages and savings in sugar factory practices:

The massecuite temperature can be regulated very closely without trouble from local cooling, local overheating, or the formation of false grain.

Each strike dropped from the pan may be held throughout almost exactly at the final pan temperature and consistency, yet if desired the temperature of the massecuite may be allowed or caused to fall gradually a few degrees, without trouble from cooling shocks or smear, so as to cause a substantial and uniform growth or accretion of existing sugar crystals.

The presence of false grain in centrifugal charges is substantially eliminated, provided only that the massecuite has been properly boiled in the vacuum pan.

The formation of crusts on the internal mixer parts is almost entirely eliminated, whereas this continued to be a substantial source of crystal loss in prior practice. The practice of washing the crusts away with large quantities of water at the end of each strike and the costs and complications attending that practice are substantially eliminated.

The elimination of false grain and the improved control over the purging qualities of centrifugal charges permit more uniform and better centrifugal operations, with lowered wash water requirements and with increased yield due both to the reduced washing and to accretions of crystals in the mixer while awaiting treatment.

The temperature of water circulated through the heating coils to maintain a desired purging condition may be substantially lowered, at a saving of heat and elimination of grain melt formerly caused in some cases by excessive water temperatures.

A further aspect of practical merit is that the improved system reduces the temperature of the air around the mixer and the centrifugal machines and thus contributes materially to the comfort of centrifugal operators, especially under warm or hot weather conditions.

It will be apparent to those skilled in the art that my invention may be embodied in various forms of apparatus without restriction to the details of construction set forth hereinabove, and I therefore desire that the invention be accorded a scope commensurate with its contributions to the art, as intended to be set forth in the appended claims.

I claim:

1. The method of handling strikes of high purity sugar massecuite to be processed in centrifugal machines which comprises dropping each boiled strike directly from the vacuum pan into a mixer tank pre-heated throughout its interior to at least approximately the temperature of the boiled strike, keeping the interior of the mixer completely enclosed against access of ambient air and protecting the mixer against any substantial rate of heat loss to the ambient air from any of its contents during the centrifuging of the strike, and at the end of the centrifuging introducing steam into the mixer to reheat its interior to at least the final pan boiling temperature before dropping the next strike.

2. The method of handling strikes of high purity sugar massecuite to be processed in centrifugal machines which comprises dropping each boiled strike directly from the vacuum pan into a pre-heated mixer, keeping the interior of the mixer completely enclosed against access of ambient air and protecting the mixer against any substantial rate of heat loss to the ambient air from any of its contents during the centrifuging of the strike, at the end of the centrifuging introducing steam into the mixer to reheat its interior at least to about the final pan boiling temperature before dropping the next strike, and in the course of the steaming draining from the mixer a fluid mixture of crystals and syrups formed by the steaming from sugary material adhering to internal mixer parts.

3. In a massecuite treating installation for high purity massecuite susceptible to false grain formation, comprising a vacuum pan and a tank therebelow to receive and hold strikes of massecuite delivered successively from the pan for direct centrifugal treatment, means including a cover over the top of the tank completely to enclose the tank contents, an enclosed downcomer connecting and sealing the pan bottom

10
15

5 with said tank to convey a strike from the pan into the tank through an opening in said cover, means formed with the walls of the tank to prevent chilling heat losses from massecuite held in the tank, and at least one steam pipe opening into the tank to introduce steam thereinto between the end of centrifuging of one strike and the reception of another.

4. A mixer to receive and hold high purity sugar massecuite susceptible to false grain formation while the massecuite is drawn off charge by charge for centrifugal treatment, comprising an elongated tank having loading spouts at the bottom with gates at their ends to deliver charges of massecuite into adjacent centrifugal machines, a cover closing the top of the tank except for an opening enclosed by a downcomer through which to receive massecuite ready for treatment, heat-insulating sheet material affixed to the walls of said tank and spouts and also to said cover, and means to introduce steam into the mixer including a steam pipe extending through the wall of each loading spout.
